UNITED STATES PATENT OFFICE.

AUGUST W. KURZ, OF NEW YORK, N. Y., ASSIGNOR, BY MESNE ASSIGNMENTS, TO
ALMEGA VENTILATION, INC., A CORPORATION OF NEW YORK.

WINDOW-VENTILATOR.

1,119,288.

Specification of Letters Patent.

Patented Dec. 1, 1914.

Application filed July 11, 1913. Serial No. 778,460.

To all whom it may concern:

Be it known that I, AUGUST W. KURZ, a citizen of the United States, residing in the borough of Manhattan, city of New York, county and State of New York, have invented certain new and useful Improvements in Window-Ventilators, of which the following is a specification.

In window ventilators of the ordinary and usual type used the area of the openings or passageways for the incoming and outgoing air are fixed; that is to say after the adjustment has once been made the openings remain as adjusted until further manual manipulation or adjustment is made. The defect of this system of ventilation is that a continuous or constant movement of air in the desired direction through the room from the opening for the incoming air to the opening for the outgoing air is not maintained. In the use of ventilators of this old type sudden drafts, due to wind or other atmospheric conditions outside of the room, will rush in through the opening designed for the egress of air. This produces the disagreeable down-drafts of cold air when the air egress is located at the top of the window and the air inlet is located at the bottom of the window. This also results in a derangement of the desired currents of air and also interferes with the inward passage of air through the inlet openings. In this old type of ventilator it is manifest that if the sudden drafts of air enter the room through both the inlet and outlet openings the ventilating system or plan is destroyed, resulting in the discomfort of the persons in the room from the fact that the vitiated air cannot escape and from the further fact that drafts of cold air enter the room from both the top and bottom of the window. It is well known that drafts of cold air from the top of a window make it practically impossible for a person to sit near the window without grave danger to his health.

It is the main object of this invention to provide a system of ventilation in which both the air inlet and air outlet will be self-adjusting and will respond to a variable atmospheric condition outside of the window and prevent sudden inward drafts of cold air through either the air inlet or the air outlet.

Another object of the invention is to provide a ventilating system which will main-

tain a movement of air through the room in a constant direction from the air inlet to the air outlet, without regard to the variable atmospheric conditions outside of the room to be ventilated.

Another object of the invention is to provide ventilating devices wherein the air outlet will so respond to changes of atmospheric conditions that it will close said air outlet and prevent inward drafts of cold air there-through.

It is also the object of this invention to provide means whereby the air inlet will so respond to atmospheric changes outside of the room to be ventilated that it will materially reduce the area of the inlet but which will not completely close it. The result of this is that air will be entering the room at all times, the area of the inlet varying in response to the atmospheric changes outside of the room.

The invention, therefore, contemplates the use of an air inlet and an air outlet, the area of the inlet varying in response to atmospheric changes, such as wind outside of the window, but at all times maintaining an opening through which air may pass into the room; and a device controlling the outlet of air from the room, said outlet varying in response to atmospheric changes outside of the room, such as wind, this outlet being capable of closing entirely to absolutely prevent any drafts of cold air rushing into the room through the air outlet. The result of this will be an air pressure in the room and as the outlet device is usually located at the top of the window said air pressure will tend to constantly maintain said outlet device open. It is manifest that the draft of cold air tending to enter the room through the air outlet must first overcome the pressure from within the room, and the pressure within the room will immediately open said air inlet the instant the dominant outside pressure is relieved.

In the drawings, Figure 1 is a vertical sectional view of a window with the ventilating devices in position, said devices being shown in end view; Fig. 2 a similar view on an enlarged scale, the ventilating devices being shown in cross sectional view; Fig. 3 a face view of the air outlet device, a portion of the said device being shown in vertical sectional view to more clearly illustrate its construction; and Fig. 4 a similar view of

the air inlet device, a portion of said device being shown in vertical sectional view to more clearly illustrate its construction.

Referring to the various parts by numerals, 1 designates the window casing which may be of any suitable form; 2 the upper sash and 3 the lower sash. These sashes are provided with the meeting rails 4 and 5; and the upper sash is provided 10 with the top rail 6 and the lower sash with the bottom rail 7. The meeting rail 5 of the upper sash is provided with a felt strip 8 which is adapted to bear on the glass of the lower sash and to prevent currents of air 15 passing into the room between said meeting rails.

The outlet device 9 is located at the top of the window frame outside of the top rail of the upper sash, said device being permanently secured to the window frame by any suitable means. The inlet device 10 is located at the bottom of the window outside of the bottom rail 7 of the lower sash, preferably resting upon the window sill and being 25 rigidly secured in position by means of screws 11 which pass through upwardly extending flanges 12 at the ends of the frame of the device. The inner surfaces of both the inlet and outlet devices are practically 30 flush with the outer surfaces of the bottom and top rails, so that said devices will not interfere with the free movement of the sash.

The outlet device consists of a box-like casing 13 having a perforated outer vertical 35 face 14 which extends entirely across the window. The bottom 15 of this case is hinged at its inner edge, as at 16, a spring 17 being provided to normally hold said bottom in its upper closed position. By 40 means of this hinged bottom any dust or dirt which accumulates within the casing may be readily discharged therefrom. The upper portion of the inner face of the case is open to form the air outlet 18. Along the lower 45 margin of this outlet is secured a felt strip 19 which bears against the outer face of the top rail 6, as shown clearly in Fig. 2. Within the case 13, at the top thereof is pivoted a depending gate or valve 20. This gate is 50 preferably made of aluminum or other extremely light material impervious to air. This gate is preferably mounted to swing very freely on its pivots so that very light currents of air will swing it from its open 55 to its closed position, and so that it will readily fall by gravity to its fully open position, as will more fully hereinafter appear. Stops 21 of felt or other suitable material are preferably secured to the ends of the casing 60 in position to be engaged by the gate 20 when the said gate is in its vertical normally open position. The felt strip 19 is extended into the case 13 and its inner edge is adapted to be engaged by the lower edge of 65 the gate 20 when the said gate is swung in-

wardly to its closed position. On the ends of the case and in position to be engaged by the ends of the gate felt strips 22 are secured so that when said gate is in its closed position the opening 18 will be completely 70 closed to prevent air passing into the room through the outlet device. The gate 20 may be formed as a single gate throughout the length of the ventilating device, or the device may be divided into sections by partition 23 and a gate provided for each compartment formed by said partition. 75

It is manifest that air under normal conditions may pass out through opening 18 under the gate 20 and out through the perforated outer wall 14 of the case 13. It is also manifest that should there be an inward rush of cold air due to wind or other atmospheric conditions outside of the window the extremely light gate 20 will swing to its 85 closed position thereby preventing any air passing into the room through the outlet device. As soon, however, as the normal conditions have been restored the gate 20 will swing down to its open position, thereby 90 restoring the normal condition of the outlet device.

The inlet device consists of a casing having a rigid top, a perforated inner vertical wall 24; an outwardly and downwardly curved outer wall 25, and a horizontal perforated intake 26 extending inwardly from the lower end of the wall 25, said intake being about midway the height of the casing. The inner end of the perforated intake 26 is 100 connected to a vertical imperforate wall 27 which extends to the bottom of the casing. Within the casing is a vertical imperforate wall 28 which extends longitudinally of the casing parallel with the perforated inner wall 24, this wall 28 together with wall 27 forming a trough-like compartment 29 within the casing. The bottom of this compartment inclines inwardly and downwardly to a longitudinally extending discharge opening 30. This opening is for the purpose of discharging any dust or dirt which may be trapped in the casing. The wall 28 is substantially the same height as the wall 27, both of said walls being approximately one-half the height of the casing. 110

Within the casing 10 at the top thereof is pivotally mounted a depending gate or valve 31. This gate is formed of extremely light material such as aluminum and is mounted 120 to swing freely on its pivots. Stops 32 are provided in the casing to be engaged by the gate 31 when said gate is in its normal vertical position. Stops 33 are arranged close to the upper end of the wall 28 in a position to be engaged by the lower end of the gate 31 when said gate is swung inwardly toward the wall 28. The gate and the wall 28 are so proportioned that when the gate is swung inwardly to the stops 33 the passage for the 125

air is restricted, said passage being only equal to the width of the stops 33, as clearly shown in Fig. 2 of the drawings. The gate 31 extends below the upper edges of the walls 27 and 28 so that the inwardly moving air must pass down around the gate 31 and then up over wall 28, the gate 31 serving as a diverting wall. It is manifest, therefore, that air cannot pass directly from the intake 10 to the inner perforated wall of the casing but will contact with the gate 31 and be diverted through the channel or trough 29. It is also manifest that the gate 31 will be swung inwardly to the stops 33 by an inward rush of air and that, therefore, unusual drafts will be prevented from passing inwardly through the perforated wall 24. The area of the air passage around and under the gate 31 will be dependent upon the 20 atmospheric conditions outside of the room; that is to say sudden drafts will swing the gate 31 toward the stop 33, thereby restricting the passageway and cutting down the amount of air passing into the room, or at 25 least preventing an increased quantity of air passing into the room. The result of this will be that the amount of air passing into the room will be substantially uniform under variable atmospheric conditions. It 30 is also manifest that the inlet device is automatic and self-regulating; the moment the sudden inrush of air ceases the gate 31 immediately falls back to its stop 32, thereby restoring the normal conditions in the casing.

Felt strips 34 are secured to the bottom of the casing, said strips being adapted to rest upon the window sill and to form a space 35 to receive the dust and dirt discharge through the opening 30 in the bottom of the case. The felt strip 36 is secured to the inner lower side of the top of the casing, said felt being adapted to bear against the bottom rail 7 of the inner sash, 40 thereby preventing air entering the room between the casing and the said sash. The outwardly and downwardly curved wall 25 forms a protecting hood for the intake 26.

It is manifest from the foregoing that the 50 air intake or inlet will be at all times open but that the area will be automatically varied to suit the variable atmospheric conditions. The object of this is to insure as nearly as practical a uniform supply of air 55 through the inlet device and to prevent sudden inrushes of air due to sudden gusts of wind or other sudden changes in atmospheric conditions outside of the room to be ventilated. It is also manifest that the outlet 60 will operate automatically to prevent any inrush of air through it, the gate or valve 20 being swung to its closed position by inward pressure of air thereon. At the same time said valve is biased toward its normal 65 position so that it will return to its open

position the instant the inward pressure is relieved. Because of the fact that the inlet device will constantly supply air to the room there will be a constant pressure within the room exerting itself against the gate 20 of 70 the outlet device. This will insure the opening of the gate 20 the instant the preponderating pressure on the outer side thereof is relieved.

It is clear that with the devices, and the 75 system of ventilation described in the foregoing, a constant movement of air in a certain direction will be maintained through the room to be ventilated and that sudden inrushes of air will be avoided.

What I claim is:

1. A system of ventilation comprising means for admitting air into a room and to permit it to flow therefrom, means to control the inward flow of air and a second 85 means to control the outward flow of air, both said means being normally in open position directly in the path of the moving air and tending to return to said open position whenever diverted therefrom, means to 90 prevent said first-named means from completely cutting off the inwardly moving air currents, the means to control the outward flow of air being adapted to be closed completely by air currents moving inwardly 95 through the outlet, whereby strong inward drafts of air will close the outlet and greatly restrict the inlet, the air pressure in the room opposing the inward drafts and restoring the air controlling means to their 100 normal positions when said air pressure and the normal tendency of the air controlling means to open, exceeds the inward air pressure.

2. A ventilating system comprising an air inlet device adapted to be located near the floor of a room, and an air outlet device adapted to be located near the ceiling of a room, a light, freely-swinging gate in the inlet device and located in the path of the inflowing air and adapted to be swung by inwardly moving air currents to greatly restrict the inlet passage, said gate normally open and tending to return to its open position when diverted therefrom, means to prevent said gate completely closing the inlet passage, a light loosely mounted, freely movable, inwardly swinging gate in the outlet device directly in the path of the outwardly moving air, said gate being normally open and tending to return to its open position and being adapted to be swung inwardly to completely close the air outlet, whereby strong inward drafts of air through both the inlet and outlet devices will close the 110 outlet and greatly restrict the inlet, the air pressure in the room opposing the inward drafts and restoring the gates in both the inlet and outlet devices to their normal open 115 positions when said pressure in the room 120 exceeds the inward air pressure.

4. tendency of the gates to return to open position exceeds the inward pressure on the gates.
5. A system of ventilation comprising means for admitting air into a room and a second means to permit it to flow therefrom, the air admitting means responding to variable inward air pressures and automatically admitting a substantially uniform quantity of air under varying inward pressures, the flow of air from the room being automatically stopped by air pressure when the inward air pressure is greater than the outward pressure or flow from the room, the means for controlling the inward flow of air and the means for controlling the outward flow of air automatically returning to their normal open condition when relieved of abnormal inward air pressure.
6. An inlet device for a ventilating system consisting of a casing, a depending freely swinging gate mounted in said casing and extending longitudinally therewith, said casing protecting the gate and inclosing it, an inlet into said casing on the outer side thereof and above the lower edge of the casing, an outlet from said casing at the inner side thereof, an upwardly extending deflecting wall between the depending gate and the inner wall of the casing, the lower edge of the gate extending below the inlet and also below the upper edge of the deflecting wall, whereby the gate will deflect the inwardly moving air and cause it to move downwardly and under the lower edge of the gate and then upwardly and over the top of the deflecting wall, the deflecting wall and the lower portion of the forward wall of the casing forming a compartment into which the lower edge of the gate projects, and a stop device to prevent the gate completely closing the passage between said gate and the deflector wall.
7. An inlet device for a ventilating system comprising a casing formed with a perforated inner vertical wall extending longitudinally thereof and a downwardly extending freely movable inwardly swinging gate mounted at the top of said casing, a horizontally arranged intake wall at the outer side of the casing and extending longitudinally thereof, the outer edge of said wall being connected to the lower end of an upwardly and inwardly curved protecting hood, said casing having a longitudinally extending channel or trough, the lower edge of the gate extending into said trough and below the upper edges thereof, said trough or channel being formed with an outlet through its bottom, and means to prevent the gate completely interrupting the inward flow of air through said device.

In testimony whereof I hereunto affix my signature in the presence of two witnesses.

AUGUST W. KURZ.
